UNITED STATES PATENT OFFICE

140,504

DESIGN FOR A LIGHTING FIXTURE

Frederick E. Gleason, Seattle, Wash., assignor to
Seattle Lighting Fixture Co., Seattle, Wash., a
corporation of Washington

Application December 13, 1943, Serial No. 111,998

Term of patent 14 years

(Cl. D48—23)

To all whom it may concern:

Be it known that I, Frederick E. Gleason, a citizen of the United States, residing at Seattle, in the county of King and State of Washington, have invented a new, original, and ornamental Design for Lighting Fixtures, of which the following is a specification, reference being had to the accompanying drawing, forming part thereof.

Figure 1 is a side elevational view of a lighting fixture showing my new design.

Figure 2 is a transverse sectional view thereof taken on line 2—2 of Figure 1.

Figure 3 is a bottom perspective view thereof. The lighting fixture, in the design which char-

acterizes this invention, incorporates a pair of fluorescent tubes supported between octagonal end plates, and enclosed within a tube, extending between the end plates, which is transparent throughout its length and over approximately half its periphery, but opaque in its remaining portion; the whole having supporting hooks mounted eccentrically of the respective end plates.

I claim:

The ornamental design for a lighting fixture, substantially as shown and described.

FREDERICK E. GLEASON.
